METHOD OF USING NATURAL GAS AS A FUEL.

SPECIFICATION forming part of Letters Patent No. 297,638, dated April 29, 1884.

Application filed November 21, 1883. (No model.)

To all whom it may concern:

Be it known that I, ADAM SCHAEFER, of the borough of Sharpsburg, county of Allegheny, in the State of Pennsylvania, have invented a certain new and useful Improvement in the Method and Means for Utilizing Natural Gas as a Fuel; and I hereby declare the following to be a full, clear, and exact description of the same, reference being had to the accompanying drawings, in which—

Figure 1 is a vertical longitudinal section of a boiler-furnace showing means adapted for carrying out my invention. Fig. 2 is a front elevation. Fig. 3 is a rear elevation. Fig. 4 is a detail perspective view of the tube *f* or air and gas mixing conduit, the gas-supply nozzle *c*, and a register or valve for regulating the amount of air which is admitted to mix with the gas.

Like letters refer to like parts wherever they occur.

My invention relates to method and means of utilizing for purposes of fuel the natural gas now so readily obtainable in various localities; and it consists, first, in combining or mixing air with the gas and heating the mixture prior to ignition, whereby a more perfect combustion, clearer flame, and greater heat is obtained than is now obtainable from natural gas; and, secondly, in apparatus for combining and heating the mixture of air and gas, as will hereinafter more fully appear.

Manufactured gas or carbonic oxide, as commonly employed for fuel, is a fixed gas, the character of which can be determined and the combining equivalent of air to produce complete combustion therewith can be ascertained; but natural gas as obtained varies in character and quality, often being surcharged with hydrocarbon vapors, and is apt to burn with a smoky flame for lack of proper amount and association of atmospheric air at the place of combustion. To overcome this smoky flame and loss of fuel, I mingle more or less air with the natural gas and heat the two together, whereby the air will take up the vaporous hydrocarbons present, proper admixture of the air and gas to facilitate combustion is obtained, and the volume of efficient fuel is augmented, so little or no loss of fuel results. The amount

of air admixed with the gas will depend upon whether or not additional air is to be supplied at the place of combustion. I prefer and have therefore shown devices wherein the entire volume of air required is mixed and heated with the gas.

I will now proceed to describe the invention more specifically, so that others may apply the same.

In the drawings, *A* indicates the walls of a boiler-furnace, wherein is set a boiler, *B*, said furnace having a combustion-chamber, *a*, and the usual flues leading therefrom to the stack. The character or class of furnace is immaterial, the boiler-furnace having simply been chosen for purposes of illustration as one of the many arts to which the invention is applicable.

At the rear of the furnace is a main or conduit, *C*, for the gas-supply, and rising therefrom are a series of smaller pipes, *c*, each provided with a valve, *d*, and by preference terminating in a nozzle, *e*.

Arranged on the bottom of or in the flue by which the products of combustion escape are tubes *f*, corresponding in number with the number of pipes *c*, and said tubes *f*, whose diameter considerably exceeds the diameter of tubes *c*, project beyond the furnace-wall at the rear end, are open, as shown, and receive the ends or nozzles *e* of tubes *c*. The open ends of said tubes *f* are guarded by registers or valves *m*, which surround the ends of tubes *c*, so that by opening the valves or registers more or less the volume of air which enters tubes *f* for admixture with the gas may be controlled. The tubes *f* extend forward through the combustion-chamber *a* and project at the front of the furnace. Tubes *f* may be composed of any number of sections, and to obtain the best results these several sections should increase in diameter as they approach the combustion-chamber *a*, or hottest part of the furnace, so as to allow for expansion of the gases and avoid the forcible delivery of the gases, which would result if expansion were not provided for. This gradual increase in diameter of the tubes will be seen by comparing tubes *f* and *f'*. (Shown in dotted line, Fig. 1.) The tubes *f*, if of iron or other material liable

to be injured by excessive heat, should be protected by a covering of sand or fire-brick.

Secured to the fire-chamber end or front end of tubes *f* are delivery-nozzles (or burners) *g*, 5 of elbow or curved form, and the diameter of this delivery-nozzle or burner gradually increases from the point of its attachment to the tube *f* toward its mouth, so that the flow of the gas, &c., may be gentle and uniform.

10 Where the gas-supply pipes *c* enter the mixing-tubes *f* they may be surrounded by a hood, *h*, if desired.

The devices hereinbefore described or their equivalents will be operated as follows in carrying out my method of burning natural gas: 15 The natural gas from the well will be conducted to the furnace by the conduit *C*, and, the valves *d* being opened the desired distance, will be delivered through pipes *c* into the open rear end of tubes *f*, the flow of the gas inducing the air-supply; or, if desired, an air-blast may be used by the usual means of producing the same. The commingled air and natural gas pass through the tubes *f* and escape from the 20 nozzles *g* into the combustion-chamber *a*, where they are ignited. The products of combustion pass backward through the waste-product flue, delivering up their heat to the advancing mixture of air and gas, and the air, as it becomes 25 heated, absorbs any vaporous hydrocarbons with which the natural gas may be surcharged, the volume of the gas is augmented, the air becomes intimately intermingled with the gas, and the whole highly heated, so that by the 30 time the combustion-chamber *a* is reached all conditions essential to a clear flame of high temperature are obtained.

I am aware that the air and gas have heretofore been heated prior to their union at the 35 place of ignition; and I am also aware that manufactured fixed gases have been mingled or intermixed with air prior to ignition, in or-

der to so associate the air and gas as to produce the mechanical conditions most favorable to complete combustion or combustion, and 45 do not herein claim either of said processes; but,

Having thus described my invention, what I claim, and desire to secure by Letters Patent, is—

1. The method herein described for burning natural gas, which consists in mixing air with the natural gas as it comes from the well and heating the admixture prior to ignition, substantially as and for the purposes specified. 50

2. In devices for admixing and burning natural gas, the combination, with a gas-supply pipe, of a gas and air admixing conduit the diameter of which is greater at the delivery end than at the receiving end, substantially as and for the purposes specified. 55

3. In devices for admixing air and natural gas and burning the same, the combination of an admixing-conduit whose diameters increase from the receiving to the delivery end, and a 60 burner or delivery-nozzle which increases in diameter from its receiving end to its mouth, substantially as and for the purposes specified.

4. In a device for admixing air with natural gas and burning the admixture, the combination, with the open-ended conduit, which gradually increases in diameter, of a gas-supply pipe projecting into its open end, where the diameter of the conduit is the least, and an expanding nozzle or burner secured to its 70 opposite end, or where the diameter of the conduit is the greatest, substantially as and for the purposes specified. 75

In testimony whereof I have hereunto set my hand this 17th day of November, A. D. 1883.

ADAM SCHAEFER.
